(57) **CLAIM**

The ornamental design for a jump rope handle, as shown and described.

DESCRIPTION

FIG. 1 is a perspective view of the jump rope handle;
 FIG. 2 is a front view thereof, the rear view, left side view and right side view being the same;
 FIG. 3 is a top view thereof; and,
 FIG. 4 is a bottom view thereof.

The broken lines illustrate environmental structure and form
 no part of the claimed design.
